W. T. Driswell

UNITED STATES PATENT OFFICE.

ST. CHARLES JACOBS, OF BROOKLYN, NEW YORK.

AMUSEMENT DEVICE.

1,366,004.

Specification of Letters Patent. Patented Jan. 18, 1921.

Application filed December 1, 1919. Serial No. 341,672.

To all whom it may concern:

Be it known that I, ST. CHARLES JACOBS, a citizen of the United States, and a resident of Coney Island, borough of Brooklyn, in the county of Kings and State of New York, have invented a certain new and useful Improvement in Amusement Devices, of which the following is a full, clear, and exact specification.

10 This invention relates more particularly to a class of devices adapted to be used for amusing persons.

My invention has for its object primarily to provide a device designed to be employed 15 at pleasure resorts and elsewhere for entertaining persons by requiring the exercise of skill to accurately throw a ball or like missile at a breakable inflated target so that the target will burst with the sound of an explosion when hit by the missile, and which is of a form whereby the target may be provided to represent the head of a person, animal or other appropriate object as well as being of a type adapted to be inflated by 20 air or gas so that currents of wind will cause the target to move in various directions in order to make it difficult of being struck. This is accomplished mainly by providing a hollow bag or casing of yielding or flexible material having an inlet for admitting air or gas under compression, and surrounding the inlet may be an annular flange whereby the inlet may be closed following inflation of the bag by wrapping a 25 cord around the flange. The bag is of a form so that when inflated it will assume approximately a spherical shape for providing an easily observable target, and on the bag may be inscribed or painted the 30 face of a person, or head of an animal or other figure to make the target attractive.

Another object of the invention is to provide a stationary body having a clamp which is manually operable for engaging 35 the flange of the bag whereby the bag following its bursting by being struck by the missile may be removed from the body and replaced with another inflated bag.

A further object of the invention is to 40 provide a form of the device whereby a group of the targets may be employed on a single support as occasion requires.

With these and other objects in view the invention will be hereinafter more fully described with reference to the accompanying drawing forming a part of this specification

in which similar characters of reference indicate corresponding parts in all the views, and will then be pointed out in the claims at the end of the description. 60

In the drawing, Figure 1 is a fragmentary view showing a perspective of one form of amusement device embodying my invention.

Fig. 2 is an enlarged elevation of one of the targets shown in the view of the device 65 illustrated in Fig. 1, and

Fig. 3 is an enlarged fragmentary detail sectional view, partly broken away, taken on the line 3—3 of Fig. 2.

In practice I may provide a support, as 70 10, formed of surface element or board 11 which may be of any suitable shape and size, though the board shown is substantially square or rectangular as well as being supported on a number of legs or standards 12. 75

On the top of the board 11 may be provided one or a group of upstanding targets, objects or figures 13, and when provided in a group the figures may be arranged in spaced rows with the figures of each row 80 also being spaced from each other. All of the figures are preferably of similar formations, each having a body 14 which may be made to represent the body of a person or animal or other object, and the body of each 85 figure is held stationary on the board 11 of the support. When the figures represent persons on each foot, as 15 and 16, of each person is provided a peg or post 17 and 18 respectively, and these pegs of each person 90 are mounted in pairs of holes, as 19, provided at suitable spaced intervals in the board.

The body 14 of each person or figure is hollow as well as having an open neck, as 20, 95 and the head 21 of each figure provides the target proper of the device. Each head or target 21 consists of a hollow bag or casing 22 which may be made of thin sheet rubber or animal tissue or other yielding material, or each target may be made of paper or like 100 flexible material of substantially an air proof texture of a fragile character so that when struck by a ball or other suitable missile the target will be broken. Leading into the interior of each target or bag is an inlet 23 to allow the bag to be inflated with gas or air under compression so that when the bag is broken its bursting will be accompanied with an explosive sound. On the exterior 110 of the bag surrounding the inlet may be an annular flange 24 to permit the inlet to be

closed after the inflation of the bag by tying a string or the like around the flange. Each bag, head or target 21 is of a form so that when inflated it will assume somewhat a spherical shape, and on the exterior of each head or bag may be painted or otherwise inscribed the face of a person, as 24^a, or other suitable figure to make the bag an attractive target.

10 The bag, head or target 21 of each figure is removably attached to the body 14 of each figure by means of a clamp or clip, as 25, which is provided at the neck 20 of the body. Each clamp may be of any preferred or well 15 known type, though the form of the clamp illustrated is composed of two substantially S-shaped members or strips 26 and 27. These strips of each clamp are disposed crosswise of each other, and the lapping central parts of the strips are held on one end of a pivot 28 provided across the neck 20 of the body 14. Each clip is thereby arranged exteriorly of the body of each of the figures 13 as well as being arranged so that 20 one of the corresponding ends of the clip protrudes above the neck of its body, while the second corresponding ends of the clip extends downwardly from the neck. The parts of the strips 26 and 27 of each clamp 30 below the pivot 28 are formed so that they are in spaced relation to serve as handles 29 and 30 and the parts of the strips of each clamp above the pivot are curved outwardly of each other and then curved inwardly so that their free ends are in normal contact for serving as coacting jaws 31 and 32. On the pivot 28 of each clamp is a spring 33 which is tensioned for causing to yieldingly force the handles 29 and 30 normally from 40 each other and in turn causing the jaws 31 and 32 to be normally forced yieldingly so that their ends abut against each other. To detachably fasten the breakable explosive target or head or bag 21 to its respective 45 body the clamp 25 of the figure is operated by forcing the handles 29 and 30 toward each other. The jaws 31 and 32 of the clamp will then be swung apart, and the flange 24 of the target or head is inserted between the 50 jaws. When the handles are released the tension of the spring 33 of the clamp will cause the jaws to engage the flange of the target which in turn will be releasably held so that persons may exercise their skill to 55 accurately throw a ball or missile for the purpose of bursting the inflated explosive target. Moreover, by making the target so that when inflated it will be lighter than air, and by retaining the target on the body, as 60 above explained, currents of air will cause the target to shift in various directions so that it will be somewhat difficult to be struck and bursted. Following the bursting of the target of one of the figures it may be removed from the body by reoperating its

clamp, and the body is then replenished with a new inflated breakable explosive target. Thus I provide a simple and efficient device for entertaining persons at pleasure resorts and elsewhere.

In the foregoing description, I have embodied the preferred form of my invention, but I do not wish to be understood as limiting myself thereto as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. In an amusement device, a stationary support, a removable inflated baglike element above the support to serve as a target, said element being of breakable material whereby it will burst when struck by a propelled missile and the element being lighter than air and part of the element being held to the support so that currents of air will cause the element to move.

2. In an amusement device, a stationary support, a removable baglike element above the support to serve as a target for being struck by a propelled missile, said element being of fragile material whereby it will break when struck by the missile and the element being inflated with gaseous fluid under compression for producing an explosive sound when bursted and the element being lighter than air as well as part of the element being held to the support so that currents of air will cause the element to move.

3. An amusement device, comprising a support, a body fixed on the support, a clamp on the body, and an inflated target held by the clamp for being struck by a propelled missile, said target being of breakable material whereby it will burst when contacted by the missile.

4. An amusement device, comprising a support, a hollow body fixed on the support, a clamp on the body, and a hollow inflatable target held by the clamp for being struck by a propelled missile, said target being of fragile material whereby it will break when contacted by the missile and the target being inflated with a gaseous fluid under compression for producing an explosive sound when bursted.

5. An amusement device, comprising a support, a hollow body fixed on the support, a clamp on the body and a hollow inflated target removably held by the clamp for being struck by a propelled missile, said target being of breakable material whereby it will burst when contacted by the missile and the target being lighter than air as well as

being held so that currents of air will cause the target to move.

6. An amusement device, comprising a support, a hollow body fixed on the support, a clamp on the body, an inflatable target removably held by the clamp for being struck by a propelled missile, said target being of fragile material whereby it will burst when contacted by the missile and 10 the target being inflated with gaseous fluid

under compression for producing an explosive sound when bursted as well as being lighter than air and held so that currents of air will cause the element to move.

This specification signed and witnessed 15 this 29th day of November A. D. 1919.

ST. CHARLES JACOBS.
